UNITED STATES PATENT OFFICE.

PETER MACGREGOR, OF OTTAWA, ONTARIO, CANADA.

FASTENING-BUTTON.

No. 868,791.

Specification of Letters Patent.

Patented Oct. 22, 1907.

Application filed January 29, 1906. Serial No. 298,552.

To all whom it may concern:

Be it known that I, PETER MACGREGOR, of the city of Ottawa, in the county of Carleton, Province of Ontario, Canada, have invented certain new and useful 5 Improvements in Fastening-Buttons, of which the following is a specification.

My invention relates to improvements in fastening buttons and the objects of my invention are to provide a device of this class to be employed in connection with 10 a fastening string as a binding or closing means, the construction of the button being such that when the string is wound around it, it will grip it and hold it firmly in position without slipping; and it consists essentially of the improved construction hereinafter more particularly described and specifically set forth in the accompanying claims.

Figure 1 shows a perspective view of a filing case with my improved fastening button applied thereto. Fig. 2 shows a sectional view through my improved fastening button. Fig. 3 shows a top view of the button. Fig. 4 is a sectional view through an alternative form which may be used when the button is employed on canvas or other flexible material.

In the drawings like letters of reference indicate corresponding parts in each figure.

Referring to the form shown more clearly in Figs. 2 and 3, *a* is a stamped metal disk, having a central, apertured, cupped portion *b*, and an annular groove *e* extended downward into proximity with the base *c*. An eyelet *g* is received within the central aperture in the cupped portion and clamps the latter against the base. An open slot *h* extends inward from the periphery of the disk and terminates at a point on the bottom of the cupped portion outside of the aperture therein.

35 The form shown in Fig. 4 differs only in that there are provided washers *n* and *o* on opposite sides of the base, the washer *n* being large and provided with an upward-projecting head *p* to coöperate with the groove *e*. This form is designed for use particularly with a base of textile or other flexible or yielding material.

One mode of use of the buttons is shown in Fig. 1,

wherein is illustrated a file or binder provided with two of my buttons *l*, *m* in the region of the binding. The binding cords, after being passed through the covers *j*, *k* of the binder and the papers contained therein, 45 are led up through the eyelets *g* in the buttons, are then drawn sidewise downward into the slots *h*, and finally wound in the space between the central cupped portion *b* and the groove *e*, this grooved region yielding upward to permit the cord to pass beneath. 50 *i* represents any suitable form of button which may be used in conjunction with a cord to hold the binder closed.

It will be seen that I have produced a button possessing a high degree of strength and utility. The central 55 cupped portion permits the button to be clamped directly against the base by means of the eyelet, which, as shown, is quite short. The formation of the open slot from the periphery of the disk to a point on the bottom of the cupped portion outside of the aperture therein permits the cord to be led directly sidewise from the top of the eyelet without having to be directed downward in order to pass beneath the groove *e*, thus obviating undue wear upon the cord, and, at the same time, the button is not seriously weakened, since the slot 60 does not extend all the way to the central aperture. 65

What I claim as my invention is:-

In a fastening of the cord and button type, the combination with a base, of a thin metal disk having an annular groove extended downward into proximity with the base 70 from, and a central cupped portion inclosed by said groove and having a central aperture, and an eyelet received within said aperture and clamping said cupped portion against the base, said disk having an open slot extending inward from its periphery across the groove and terminating at a point on the bottom of the cupped portion outside of the aperture therein. 75

Signed at Ottawa, in the Province of Ontario, this 24th day of January, 1906.

PETER MACGREGOR.
